[57] **CLAIM**

The ornamental design for a boat hull, as shown and described.

DESCRIPTION

FIG. 1 is a top, rear perspective view of a boat hull showing my new design;

FIG. 2 is a top plan view thereof;

FIG. 3 is a side elevational view thereof, the opposite side elevational view being a mirror image of that shown.

FIG. 4 is a bottom plan view thereof;

FIG. 5 is a cross sectional view thereof taken along line 5—5 of FIG. 3;

FIG. 6 is a cross sectional view thereof taken along lines 6—6 of FIG. 3;

FIG. 7 is a front perspective view thereof;

FIG. 8 is a rear perspective view thereof.

FIG. 1

FIG. 2
